ELECTRODYNAMIC VIBRATOR

Hugo Benioff, La Canada, Calif., assignor to Submarine Signal Company, Boston, Mass., a corporation of Maine

Application April 18, 1941, Serial No. 389,209

5 Claims. (Cl. 177—386)

The present invention relates to the art of sound transmission and reception by the use of compressional waves and more particularly relates to this art as applied to propagating media heavier than air, and in particular to the art of submarine signaling in frequency ranges in and above the limit of audibility of the human ear for the production of directive sound waves and the reception of sound waves by directive receivers.

In the present invention for the reception of directive waves and the propagation of sound beams a plurality of similar vibrators mounted on a radiating element and operative in substantially the same manner from an electric source may be used for the creation of the sound waves. Each vibrator in the present invention is set into vibration by means of the reaction between an alternating current flowing in a coil fastened to the vibrator and a constant magnetic field. These driving coils are mounted each at one end of the vibrators and the group thus forms a system for properly converting the electric energy to acoustic energy as will be more fully explained below.

In the present invention the electrical driving means is positioned at the very end of the vibrating system where the greatest amplitude of motion of the vibrator is obtained. The driving element comprises a coil rigidly mounted at one end of the vibrator in such a manner as not to interfere with the propagation of the mechanical or acoustic wave in the tube upon which the coil is mounted.

Further merits and advantages of the present invention will be more readily understood from the description given in the specification below and taken in connection with the drawings showing an embodiment of the invention in which Fig. 1 shows a central section through the device; Fig. 2 shows a section on the line 2—2 of Fig. 1; Fig. 3 shows a section on the line 3—3 of Fig. 1; Fig. 4 shows an enlarged portion of a section of Fig. 1 with a slight modification in the construction of the magnetic circuit; and Fig. 5 shows a section on the line 5—5 of Fig. 1.

In the drawings there is provided a casing 1 on the forward end of which may be mounted a diaphragm 2 which may be round or hexagonal as indicated in Fig. 3. The central section 3 of this diaphragm is made of a plate preferably integrally formed with the flange edges 4 and joined to it by means of the continuous web 5 running all the way around the central heavy plate 3. The web 5, as indicated in Fig. 2, is in a hexagonal form, but other forms may be used, depending upon the

construction of the driving units 6, the purpose being to nest the units 6 together in such a fashion as to cover substantially the whole central section 3 of the diaphragm.

5 The unit 6 comprises a heavy base element 7 of hexagonal or other desirable form for nesting the units together, which base element 7 narrows and tapers upward with sloping sides 8 to a symmetrically located mechanically vibratable tube 9 10 which is preferably formed integral with the base member 7. The unit 6 as a whole is mounted to the plate 3 preferably by means of a centrally located machine screw 10 passing through the base 7 and threading into the plate 3, clamping 15 the unit 6 direct to the plate. It is essential that this joint be rigid and tight and preferably the joining faces are cemented together by means of cement indicated at 11. The tube 9, which may be slotted longitudinally, should have a diameter 20 approximately one-half that of the base member 7. A solid rod or bar with some mass at its free end may be used in place of the tube 9 but in general the tube is preferable. The tube diameter should preferably in all cases be less than 25 one-half wave length of the wave propagated in the material of the unit and it may be smaller than this. Essentially the unit 6 and the section of the plate 3 immediately below it, to which the unit is fastened, form longitudinally of the tube 30 a one-half wave length system at the desired frequency of vibration with the node near the base element 7 and in this manner the vibration at the free end of the tube 9 may be made large compared with the amplitude of vibration in the plate 35 3. The free end of the tube 9 is provided with a coil 12 which may be independently formed on a non-conducting form such as glass, "Lucite," or some such material, and rigidly cemented at the end of the tube 9. The coil 12 is short in length, 40 generally not longer than approximately one-half the tube diameter. This coil is immersed in air-gap 13 which is supplied with magnetic flux by means of the magnetic circuit comprising the shell 14 which is composed of an upper plate-like member 15 with downwardly extending arms 16 and 16' by which the magnetic field unit is fastened to a soft iron plate member 17 by means of the screws 18. The plate member 17 has its pole faces 19 narrowed to increase the flux concentration. The plate member 17 and its pole pieces 50 19 are preferably made of soft iron so as to offer a low reluctance path for the magnetic flux, while the member 15 with its downwardly extending arms 16 and 16' may be made of "Alnico" or some similar metal that provides a very powerful per-

manent magnet where a permanent magnet is used.

The plate 17, as will be seen in Fig. 3, is provided with numerous airgaps 13. Centrally located within the tube 9 for each tube is a projecting core 20 fastened to the "Alnico" plate by means of the screws 21. The magnetic circuit for each coil 12 is therefore completed through the plate 15, the downwardly extending arms 16 and 16', the airgap 13 and the central core 20. If desired, as indicated in Fig. 4, the hollow space 22 around the central core 20 might be filled by means of a direct current magnetizing coil 23. In this case, of course, it is preferable to make the central core 20 and the plate 15 of the same material and in one piece and this, of course, would preferably be soft magnetic iron. The direct current magnetizing system may be supported by the plate 17 resting upon a shoulder 24 on the wall 25 of the casing 1.

In the operation of the system, which may be used either as a transmitter or a receiver of sound waves, alternating current of the desired frequency is impressed upon the coil 12 and direct current in the magnetizing field unless a permanent magnet is used. The units 6 will vibrate substantially independently at the driving frequency with equal amplitudes, thus providing a uniform vibration of the whole plate 3. The device described is resonant at a frequency in which a node is produced in the tubes 9 near the base 7. The units 6 are made similar and all are similarly mounted so that the nodes in each unit form approximately a plane parallel to the plane of the plate 3. By making the surface dimension of the plate 3 many times the wave length in the medium, the plate will produce a directive beam as a transmitter, and as a receiver will respond to waves approaching only from a corresponding sector generally normal to the plate surface.

Having now described my invention, I claim:

1. A device for producing or receiving compressional waves comprising, in combination, a casing having a radiating plate, a plurality of electrodynamically driven resonant vibrator units each comprising a solid metallic base element having a large mass comparative to the rest of the resonant unit, each such base element being rigidly mounted within said casing on said radiating plate, said units each having a comparatively thin tube extending from the base and having at its free end a driving coil, said tube comprising the elastic element of the vibrator and said base element being substantially inelastic in the operation of the vibrator, the combined elements forming with the radiating plate a half wave length resonant vibrating system means providing a magnetic field in which each of said coils is positioned whereby said device may be used for sound transmission and sound reception.

2. A device for producing or receiving compressional waves comprising, in combination, a casing having a radiating plate, a plurality of electrodynamically driven resonant vibrator units each comprising a solid metallic base element having a large mass comparative to the rest of the resonant unit, each such base element being

rigidly mounted within said casing on said radiating plate, said base elements being nested together in approximately abutting positions, said base elements having comparatively thin tubes extending upwards and integrally formed therewith, each having at their free ends a driving coil, said tube comprising the elastic element of the vibrator and said base element being substantially inelastic in the operation of the vibrator, the combined elements forming with the radiating plate a half wave length resonant vibrating system and means providing magnetic fields for each of said driving coils.

3. A device for producing or receiving compressional waves comprising, in combination, a casing having a radiating plate joined thereto in a thin web extending entirely around the plate, a plurality of electromagnetically driven resonant vibrator units each comprising a solid metallic base element having a large mass comparative to the rest of the resonant unit, such units being nested together covering the entire plate and rigidly held thereto, said vibrators each having extending from the side opposite said plate a comparatively small but elongated thin driving tube, the end of said driving tube having current-conducting means and means immersing said current-conducting means in a magnetic field the vibrators with the tube and base elements, together with the plate, forming a resonant, half wave length, vibrating system.

4. A device for producing or receiving compressional waves comprising, in combination, a casing having a radiating plate joined thereto in a thin web extending entirely around the plate, a plurality of electromagnetically driven resonant vibrator units each comprising a solid metallic base element having a large mass comparative to the rest of the resonant unit, such units being nested together and covering the entire plate and rigidly held thereto, said vibrators each having extending from the side opposite said plate a comparatively small but elongated thin driving tube, the end of said driving tube having current-conducting means and means immersing said current-conducting means in a magnetic field, said current-conducting means being short in length compared to the length of said tube and the vibrators with the tube and base elements, together with the plate, forming a resonant, half wave length, vibrating system.

5. A device for producing or receiving compressional waves comprising, in combination, a casing having a radiating diaphragm, a great number of electrodynamically driven vibrators rigidly mounted and nested closely together on said radiating plate within said casing, said vibrators comprising a small tube member and a large end mass member having a base substantially larger than the cross-sectional tube area, a driving coil short in length compared to the length of the tube mounted at the end of the tube and means supplying an electromagnetic field in which said driving coil is positioned the vibrators with the tube and base elements, together with the plate, forming a resonant, half wave length, vibrating system.

HUGO BENIOFF.
